US0D1112977S

(12) **United States Design Patent** (10) **Patent No.:** **US D1,112,977 S**
(45) **Date of Patent:** **** Feb. 10, 2026**

(54) **SLOW FEEDER**

(71) Applicant: **Sijia Lan**, Guangzhou (CN)

(72) Inventor: **Sijia Lan**, Guangzhou (CN)

(**) Term: **15 Years**

(21) Appl. No.: **29/986,413**

(22) Filed: **Jan. 17, 2025**

(51) **LOC (15) Cl.** **30-03**

(52) **U.S. Cl.**

USPC **D30/129**

(58) **Field of Classification Search**
